UNITED STATES PATENT OFFICE.

LAUNCELOT EUSTACE SMITH, OF SOUTH SHIELDS, CORNELIS ZULVER, OF LONDON,
AND HERBERT ALEXANDER THOMPSON, OF NORTH SHIELDS, ENGLAND.

LIQUID-FUEL FITTING FOR FURNACE-FRONTS.

1,393,646.

Specification of Letters Patent.

Patented Oct. 11, 1921.

Application filed September 6, 1919. Serial No. 322,211.

To all whom it may concern:

Be it known that we, LAUNCELOT EUSTACE SMITH, a subject of the King of Great Britain, managing director, Smiths Dock Company, Limited, High Docks, South Shields, in the county of Durham, England, CORNELIS ZULVER, engineer, a subject of the Queen of the Netherlands, of St. Helens Court, Great St. Helens, in the city of London, England, and HERBERT ALEXANDER THOMPSON, engineer, a subject of the King of Great Britain, of 9 Cleveland Terrace, North Shields, in the county of Northumberland, England, have invented a new and 15 useful Improvement in Liquid-Fuel Fittings for Furnace-Fronts, of which the following is a specification.

This invention relates to improvements in liquid fuel fittings and in the manner of 20 mounting the same in forced or assisted draft furnace fronts of the kind comprising front and back plates spaced apart.

In the specification accompanying an application for Letters Patent Serial No. 25 322,212, filed September 6, 1919, a constructional arrangement is described for mounting liquid fuel burners in forced or assisted draft furnace fronts outside the tubular firing opening closed by the fire door, the burners being arranged within air supply tubes 30 extending through the front and back plates of the furnace front.

According to this invention in place of the air tubes passing through both plates, air 35 cones are provided which pass through the back plate only. The burners supported in burner holders pass through holes in the front plates and extend across the air heating chamber between the front and back 40 plates to positions respectively within the said air cones. If desired, the burners can be fitted with regulator cones which may be fixed or adjustable along the burners within the air cones.

45 The improved liquid fuel fittings can be readily applied to existing furnace fronts of coal fired furnaces to adapt the same for working with coal and oil fuel either separately or together. They can be for instance, applied to coal burning forced or assisted draft furnace fronts of the Howden type, the air cones being arranged so that they are inclosed within the air heating 50 chamber close to the firing opening, the removable saddle plate being made of sufficient size for this purpose.

55 The accompanying drawing shows how the said invention may be conveniently and advantageously carried into practice. In this drawing:

60 In this drawing:

Figure 1 is a sectional view, on the line 1—1, Fig. 2, of a Howden type furnace front having this invention applied thereto.

Fig. 2 is a sectional plan view of the same.

Fig. 3 is a vertical longitudinal section taken on the line 3—3 in Fig. 1.

65 As shown in this drawing *a* is the front plate and *b* the back plate which together with the saddle plate *c* inclose an air heating chamber *d* outside the firing opening *e*.

70 Burners *f* are held in burner holders *g* fitted in holes in the front plate *a* to which they are secured by flanges *h*. Air cones *i* pass through holes in the back plate *b* to 75 which they are secured by flanges *j*. Air regulator cones *k* are slidably mounted on the burners within the cones *i* but these cones may be fixed on the burners. When applying the invention to existing furnace 80 fronts, if the spigot and rib *l*, *l'* for supporting the saddle plate *c* are not of a suitable shape and dimensions to make a joint with the saddle plate along all its edges, the said plate may be formed with flanges *m* to 85 abut against the said spigot and rib where necessary to form a closure, but the spigot and rib may be made of suitable shape so that the plate *c* may be made without flanges. Air admission valves *n* of the well known 90 kind are provided on the saddle plate *c*.

What we claim as our invention and desire to secure by Letters Patent is:

95 1. In combination, a furnace front having a firing opening, front and rear plates secured about the opening, a saddle plate connecting said front and rear plates and forming therewith an air heating chamber about the firing opening, said air heating chamber being in controlled communication with the 100 atmosphere, burners held in said front plate and projecting through the air heating chamber, air cones mounted in said rear plate and setting up communication with the interior of the furnace and said air heating 105 chamber, the inner ends of the burners ly-

ing in said air cones, and regulating cones fitted within said air cones, substantially as described.

2. In combination, a furnace front having a firing opening therein, front and rear plates spaced apart and extending about said firing opening, a saddle plate connecting the front and rear plates at their outer edges and constituting therewith an air heating chamber, means for controlling the supply of atmospheric air to said chamber, burners having their outer portions mounted in said front plate and projecting into and through

said air heating chamber angularly toward the axis of the firing opening, air cones carried by said rear plate and receiving the inner ends of said burners, said cones communicating with the chamber and with the interior of said furnace, and movable regulating cones on the inner ends of said burners having adjusting means extending on the exterior of said front plate, substantially as described.

LAUNCELOT EUSTACE SMITH.

CORNELIS ZULVER.

HERBERT ALEXANDER THOMPSON. [L. S.]
